Primary Examiner — Mark A Goodwin(74) *Attorney, Agent, or Firm* — Miller Canfield(57) **CLAIM**

The ornamental design for a cultivator sweep as shown and described.

DESCRIPTION

FIG. 1 is a top, front perspective view of a cultivator sweep showing my new design;

FIG. 2 is a left side view thereof;

FIG. 3 is a right side view thereof;

FIG. 4 is a top plan view thereof;

FIG. 5 is a bottom plan view thereof;

FIG. 6 is a front view thereof; and,

FIG. 7 is a rear view thereof.

The broken lines in the drawings are included for purposes of illustrating portions of the cultivator sweep which form no part of the claimed design.
